UNITED STATES PATENT OFFICE.

BENJAMIN S. SMITH AND RICHARD NORVILLE WATSON SMITH, OF PAISLEY, SCOTLAND.

MACHINE FOR SETTING CARPET-WARPS.

No. 880,169.

Specification of Letters Patent.

Patented Feb. 25, 1908.

Application filed November 22, 1905. Serial No. 288,566.

To all whom it may concern:

Be it known that we, BENJAMIN SINCLAIR SMITH and RICHARD NORVILLE WATSON SMITH, both subjects of the King of the 5 United Kingdom of Great Britain and Ireland, and residing at Paisley, Renfrewshire, Scotland, have invented a certain new and useful Machine for Setting Carpet-Warps, of which the following is a specification.

10 The invention has for its object the provision of mechanical devices for setting the tuft yarns (which form the pile on the carpet) on the wide bobbins used in weaving what are known in the trade as imperial 15 Axminster carpets.

The invention consists of a jacquard or like apparatus working in conjunction with a winding machine and a frame or bank to carry any desired number of bobbins. The 20 jacquard raises or lowers or raises and then lowers the colored yarns as selected by the card in the usual known way the height desired so that each selection of the colored 25 yarns by each card is then wound on a wide bobbin separately (the width of the wide bobbins on which the yarns are wound being equal to the width of the carpet). The length of the colored yarn wound on each of the wide bobbins is as arranged according 30 to the length of the pile of the carpet and the quantity of repeats of the design that is to be woven. The wide bobbins are afterwards arranged in the known manner on an endless chain and operated upon by fingers or nippers 35 in the loom in the manner usual in weaving imperial Axminster carpets. In the past this setting of the colored yarns according to the painted design, has been done by hand labor. A frame being made to hold 190 40 or other quantity of bobbins, the end of the yarn of each bobbin on the frame is taken and arranged according to the design to be made, on one large bobbin 27" wide or more or less according to whether the carpet to be 45 made is to be 27" wide or more or less, then the 190 threads are wound on to this wide bobbin, the length of the yarn wound being according to the number of yards of carpet to be woven.

50 The number of bobbins to be handled by the operator is very great, according to the length of the design that is being made. For example, to set or arrange those wide bobbins for a design 36" long with 8 rows of 55 tufts of yarn to the inch of the carpet, would

require the operator to arrange the frame of 190 bobbins by 36 by 8 equaling 54,720 operations. In our method we arrange in a frame 3800 bobbins more or less. We paint the design to suit any number or all of these 60 3,800 bobbins. In the jacquard we have 3,800 tail cords more or less each controlling one of the 3,800 colored yarn threads.

The card when taking its impression on the jacquard operates so that when the lifts 65 of the jacquard are raised 190 of the ends of the colored threads are presented to an arranged level.

Any mechanical arrangement can be used to grip the 190 ends and pull them over the 70 large bobbins 27" wide. We prefer to wind on to each large bobbin enough of the yarns for one row and the repetitions thereof in the repeats of the pattern for a carpet say 45 yards long, or even for say four to five times 75 this length of carpet, but obviously in place of using only one such bobbin for carrying such lengths of yarn two or more may be used. The attendant fixes those ends to the bobbin in the usual way and by the operation 80 of a clutch lever causes the winding mechanism to act on the wide bobbin, which is rotated as many times as desired according to the number of yards of carpet that are to be woven. If a design is 36" long and there 85 are 8 rows of tufts to the inch of the carpet, then the jacquard has to operate 36 times by 8 which equals 288 operations, compared with the hand manner of doing this before this invention, of 54,720 operations for the same 90 size of design and quality of carpet to be made.

Another known way of weaving of this carpet is by having a frame at the back of the loom with a certain number of bobbins in 95 it. Each end of yarn of each colored bobbin is controlled by a jacquard tail or wire, but as the jacquard has to operate for each row of tufts or 288 times to the yard of carpet woven (if there are 8 rows of tufts to 100 the inch on the carpet) it is a slow expensive method, compared to our invention, in which the jacquard in operating 288 times could set the tuft yarns to weave 400 yards of carpet thus doing 400 times the work. 105

In the accompanying drawings which illustrate the invention Figure 1 is a side elevation of part of the tuft setting and winding apparatus. Figs. 2 and 3 are vertical and horizontal sections respectively of the yarn 110

carrier. Fig. 4 is a transverse section of the bar which raises the yarn carriers and is shown in engagement with an extension of one of said carriers. Fig. 5 shows one of the 5 tilters which are adapted to intercept the downward movement of the yarn carriers. Fig. 6 is an elevation of the jacquard or selecting machine and lever connections and Fig. 7 is an elevation (in part section) of the 10 jacquard machine fitted on the top of the tuft setting and winding frame. Fig. 8 is an elevation of part of the tuft setting and winding frame with cams and connections for operating several parts of the machine. 15 Figs. 9 and 10 are part elevations at right angles to each other showing the driving gear. Fig. 11 is an elevation and Fig. 12 a plan to an enlarged scale showing detail views of the gripper, while Fig. 13 is an elevation showing the guillotine also to an enlarged scale. Figs. 14 and 15 are detail views of a disk hereinafter referred to.

As shown, the tails or cords J of the jacquard or tuft setter which is of ordinary construction, in lieu of carrying weights are each attached to a short pivoted lever *t* which we term a "tilter". The several tilters are normally in an inclined position out of action, but such of them as are operated by the card, 20 namely one in each row, are brought to a horizontal position as is indicated at *t*¹ (Figs. 1 and 4), in which position each serves to intercept the downward movement of a corresponding yarn carrier T and bringing said carrier to rest. The carriers T each carry a 25 number of ends of yarns Y, in the present instance 20, which pass thereto from bobbins and are led through separate orifices in the carriers and held by tension springs as indicated to a larger scale at Fig. 2.

The jacquard machine has 20 rows of needles each row consisting of 252 needles. There are 20 rows of tilters *t*, and 252 tilters in each row. Each of the tilters is attached 30 to a tail J, connecting to an upright *a*, so that the needles *a*¹ of the jacquard when operated on by one of the punctured cards *a*² or design operate on the tilter through the tail on the colored yarn in the carrier as required to 35 make the design, as has been arranged by puncturing the card in the usual known way.

There are 252 carriers T across the machine and in each carrier there are 20 openings. In 40 each opening there is a spring *s* to act as a tension on each thread of colored yarn Y that is threaded through each of the openings.

At the back of the machine the usual bank or frame is arranged to hold 5040 bobbins on which are wound all the colored yarns, one 45 color only being on each of the bobbins of the 5040, and the threads of those bobbins are threaded through the openings of the carriers, each thread in a separate opening.

The tilters *t* are raised by the usual raising 50 lifter *a*³ provided with knives *a*⁴ adapted to

engage with the selected uprights *a* to which the tail cords J are attached. The carriers T have guide rods R attached to them working in a frame top and bottom. The top guide rods R are each formed into separate hooks *h* *h*¹, as shown particularly at Fig. 4, the one side *h* of which is formed for raising the yarn carriers T by means of the bar H, at the period when a puncture card *a*² is being pressed on the needles *a*¹; the hook *h*¹ on the other side is formed to catch on the tilters *t* that have been raised into the position to catch them according to which tilters have been operated on by the knives *a*⁴ of the usual raising lifter *a*³; and in this way the colored 70 yarns Y in the carriers T as arranged for the design are brought to one level such that they may be engaged by a gripper G operated by mechanism hereinafter referred to.

As shown at Figs. 9 and 10, the first motion shaft F is provided with a fast pulley F¹ and a loose pulley F² and has also secured to it a pinion wheel F³ adapted to gear with a spur wheel F⁴ on a shaft F⁵ on which are mounted clutches G² and D², the male portions of which are operated by hand levers and connections G¹ and D¹ to engage with the female portions which are loosely mounted on the shaft F⁵ and which carry pinion wheels g¹ and d¹. The pinion g¹ gears with a 75 spur wheel g² on a shaft g, said spur wheel being arranged to operate the gripper G through crank pin and lever connections G³. The pinion d¹ gears with a spur wheel d keyed to a shaft D. The shaft D has secured to it 80 at each end cams E E¹, (Fig. 8), which respectively operate the top and bottom knives of the guillotine K through lever connections k, and the shaft D also carries a cam E² which operates (through lever connections L) 85 the bar H adapted to engage with the yarn carriers T. By means of a chain m and chain wheels m¹ the shaft D also drives a shaft M at each end of which are secured cams M¹, M², (Fig. 7), arranged to operate the jacquard 90 or selecting mechanism through lever connections M³, M⁴, which respectively operate the raising lifter a³ and the jacquard card barrel.

In the operation of the machine:—The 115 first motion shaft F drives the shaft F⁵ through the gear wheels F³ F⁴ and by the attendant operating the hand lever connections G¹ the female portion of the clutch G² is engaged by the male portion and so communicates motion from the pinion g¹ to the spur wheel g² on the shaft g which spur wheel g², through crank and lever connections G³, operates the gripper G which moves forward and grasps the 252 ends of colored threads 120 placed in position and pulls them over a setting bobbin B centered on a spindle B¹. The gripper mechanism is then automatically stopped through the action of springs g⁷ (Fig. 9) disengaging the sliding male portion of the 130

clutch G² from the loosely mounted female portion, the movement of which male portion of the clutch is effected when a recess g³⁰ in a rotatable disk g⁶ (of the type shown at 5 Figs. 14 and 15) on the shaft g, comes opposite a roller g³ on the end of one of the lever connections G¹. The edge g³¹ of said disk g⁶ (Figs. 14 and 15) is arranged to keep the male portion of the clutch G² in engagement 10 with the female portion during one revolution of the shaft g, by contacting with the roller g³ on the lever connections G¹ which operate the male portion of the clutch G². The attendant now fixes, in the usual known 15 manner, the 252 threads on the bobbin B, and opens by hand the jaws of the grippers G, after which the bobbin is set in motion and the desired number of inches of yarn is wound on the bobbin. Motion is communicated 20 from the shaft F to the bobbin spindle B¹ by a sprocket wheel F²⁰ and chain F²¹ gearing with a sprocket wheel B³ loosely mounted on the spindle B¹ the face of which wheel B³ has recesses adapted to be engaged 25 by pins B³¹ on a sliding clutch portion B⁴, operated by a hand lever B⁵. When the desired number of inches of yarn is wound on the bobbin B, the winding mechanism is stopped by withdrawing by means of the 30 hand lever B⁵ (Fig. 8) the clutch B⁴ from engagement with the loosely mounted sprocket wheel B³. The attendant now operates (through the lever connections D¹) the male portion of the clutch D² which engages with 35 its female portion against the power of springs d⁵, and through the intermediary of the gearing d¹, d, drives the shaft D and likewise the cams E E¹ (Fig. 8), the latter (through the connections k) causing the guillotine 40 knives K (shown particularly at Fig. 13) to cut the 252 ends of thread and return said knives to their normal position. The ends of the thread having been cut the bar H, and likewise the yarn carriers T, is raised 45 by the cam E² and lever connections L. The next card of the design is then brought against the needles a¹ by the action of the cam M² and connections M⁴. Thereafter the raising lifter a³ is caused to actuate the selected tilters t, by means of the uprights a and tail cords J. The bar H and the yarn carrier T are now lowered and each yarn carrier T is stopped by a corresponding tilter t whereby the desired color of yarns carried by 50 it is brought into line with the gripper G. The shaft D then stops automatically on account of a roller d², attached to one of the lever connections D¹ entering a recess d³ in a disk d⁴ on the shaft D, thus releasing the 55 male portion of the clutch D² which is disengaged from the female portion by the springs d⁵ (Fig. 10), the edge of the disk d⁴ having previously acted on the lever connections D¹ during one revolution of the shaft in a similar 60 manner to the disk g⁶, Figs. 9 and 10. The

bobbin B is now removed, replaced by an empty bobbin and the several operations repeated to fill a fresh bobbin.

The loosely centered jaws of the gripper G, particularly shown at Figs. 11 and 12, are arranged to be opened by operating a disk W having slots w¹ adapted to engage with pins w on the gripper jaws, which are retained in the open position by a pawl W¹ engaging with ratchet teeth W² on the disk W. When 70 the gripper G moves forward and is in position to grip the threads the pawl W¹ contacts with a projection W³ on the framing which carries the upper knife of the guillotine K, and releases the pawl thus allowing the jaws 80 of the gripper to close. When the threads Y have been pulled into position, and fastened on the bobbin B in the usual known manner, the gripper jaws are opened by manipulating a handle W⁴ on the rotatable 85 disk W whose ratchet teeth are engaged by the pawl W¹ to retain the jaws in the open position. The gripper jaws are loosely pivoted on the shaft x and in their forward and rearward travel are supported at each end 90 on a track x¹ by a roller x² (Figs. 8, 10 and 12.)

The specific construction of the machine herein illustrated may be varied without departing from our invention, the essential feature of which is the setting of the tuft 95 yarns for weaving imperial Axminster carpets or similar fabrics by a jacquard apparatus or pattern mechanism or any apparatus controlled by a punctured card or like device operating in combination with winding mechanism.

Having now described our invention, what we claim and desire to secure by Letters Patent of the United States is:—

1. Apparatus for setting and winding tuft 105 or pile yarns for use in weaving imperial Axminster carpets comprising in combination winding mechanism including a wide bobbin and pattern mechanism for selecting the yarns to be wound on said bobbin, as described.

2. Apparatus for setting and simultaneously winding differently colored tufts or pile yarns for use in weaving imperial Axminster carpets, comprising, in combination, 115 winding mechanism including a wide bobbin, mechanism for selecting the yarns to be wound on said bobbin, and jacquard apparatus controlling said selecting mechanism.

3. Apparatus for setting and simultaneously winding differently colored tuft or pile yarns for use in weaving imperial Axminster carpets, comprising, in combination, winding mechanism including a wide bobbin, mechanism for selecting the yarns to be 125 wound on said bobbin, jacquard apparatus controlling said selecting mechanism, and devices for severing the yarns on the completion of the winding operation.

4. Apparatus for setting and simultane-

ously winding differently colored tuft or pile
yarns for use in weaving imperial Axminster
carpets, comprising, in combination, wind-
ing mechanism including a wide bobbin,
mechanism for selecting the yarns to be
wound on said bobbin, jacquard apparatus
controlling said selecting mechanism and de-
vices for bringing the selected yarns to said
bobbin.

In testimony whereof we have signed our 10
names to this specification in the presence of
two subscribing witnesses.

BENJAMIN S. SMITH.
